(57) **CLAIM**

The ornamental design for an electrical junction box, as shown and described.

DESCRIPTION

FIG. 1 is a top, side perspective view of an electrical junction box of our new design;
FIG. 2 is another top, side perspective view thereof;
FIG. 3 is a top plan view thereof;
FIG. 4 is a front elevation view thereof, the rear view being identical;
FIG. 5 is a right side view thereof, the left side view being identical;
FIG. 6 is a bottom plan view thereof;
FIG. 7 is a front, right, bottom perspective view thereof;
FIG. 8 is a top plan view of the electrical junction box of FIG. 1;
FIG. 9 is a front elevation view thereof
FIG. 10 is a right side view thereof, the left side view being identical;
FIG. 11 is a bottom plan view thereof; and,
FIG. 12 is a front, right, bottom perspective view thereof. The dash-dash broken lines in the drawings are for the purpose of illustrating environmental subject matter and portions of the electrical junction box that form no part of the claimed design.
